ABSTRACT

A printer with a hammer actuating mechanism comprising elongated drive-ratchet and control-cam shafts mounted in spaced parallel relationship and a plurality of pivotal hammers extending transversely of the shafts. A drive pawl pivotally mounted on each hammer arm is engageable by the drive-ratchet shaft for pivotal actuation of the hammer for producing a printout and the control-cam shaft is rotatable for releasing the drive pawls for engagement by the drive-ratchet shaft. A pivotal control arm is operable by an electromagnet for actuation by the drive-ratchet shaft in the manner of the hammer actuation to rotate the control-cam shaft for releasing the drive pawls.

SHEET 2 OF 2

PRINT HAMMER ACTUATING MECHANISM

BRIEF SUMMARY OF THE INVENTION

The present invention relates generally to printers of the type having one or more print hammers for producing a printout and more particularly to a print hammer actuating mechanism having a drive shaft providing power for actuating the hammers.

It is a principal aim of the present invention to provide a new and improved print hammer actuating mechanism for individually connecting a plurality of print hammers for actuation by a common drive shaft.

It is another aim of the present invention to provide a new and improved electromagnetically operated print hammer actuating mechanism which provides a single printout for each energization of its electromagnetic operator.

It is another aim of the present invention to provide a new and improved print hammer actuating mechanism which permits employing any desired number of hammers.

It is a further aim of the present invention to provide a new and improved print hammer actuating mechanism which provides reliable operation over a long service-free life.

Other objects will be in part obvious and in part pointed out more in detail hereinafter.

A better understanding of the invention will be obtained from the following detailed description and the accompanying drawing of an illustrative application of the invention.

BRIEF DESCRIPTION OF THE DRAWINGS

In the drawings:

FIG. 1 is a side elevation view, partly broken away and partly in section, of a printer incorporating an embodiment of a print hammer actuating mechanism of the present invention.

FIG. 2 is a top plan view, partly broken away and partly in section, of the print hammer actuating mechanism.

DESCRIPTION OF THE PREFERRED EMBODIMENT

Referring now to the drawing in detail, a printer 10 incorporating an embodiment of a print hammer actuating mechanism of the present invention comprises an elongated drive-ratchet shaft 12 which is continuously rotated (e.g., at 1,200 RPM) by a suitable electric motor (not shown), an elongated cam or hammer control shaft 14 (mounted with the drive-ratchet shaft 12 in laterally spaced parallel relationship), and a plurality of separate print hammer mechanism 20 (only one of which being shown in the Figure) mounted in aligned or stacked relationship for cooperation with the shafts 12, 14.

Each hammer mechanism 20 comprises a generally L-shaped hammer 22 pivotally mounted on a support shaft 24 and having an enlarged head 26. The hammer 22 is operable for performing a printout by pivoting the hammer 22, in the clockwise direction as viewed in the Figure, into engagement with a strip of paper 28 lying adjacent the type character 30 of a print wheel 32. The print hammer normally rests in its withdrawn pivotal position shown in full lines in the Figure in engagement

with a support plate 34. A hammer drive pawl 40 pivotally mounted on the hammer 22 has a first hooked end 42 having a shoulder 43 engageable by a drive shoulder 44 of the drive-ratchet shaft 12 and a second tail end 46 engageable with the cam shaft 14. A tension spring 48 connected to the tail end 46 of the hammer drive pawl 40 provides for biasing the pawl 40 into engagement with the drive-ratchet shaft 12 and for biasing the hammer 22 to its withdrawn pivotal position shown in full lines in the Figure.

A tension spring 50 is connected to the cam shaft 14 for holding the cam shaft 14 in its normal angular position shown in the Figure where its outer cylindrical cam edge 52 is engageable with the hammer drive pawls 40 to hold or latch them out of engagement with the drive-ratchet shaft 12. The hammer control cam 14 when rotated approximately 25° against the bias of the return spring 50, in the clockwise direction as viewed in the Figure, substantially simultaneously unlatches or releases the hammer drive pawls 40 for engagement with the drive-ratchet shaft 12, whereupon the drive shoulder 44 of the shaft 12 engages the pawl shoulders 43 to pivot the hammers 22 upwardly against the bias of their return springs 48 to produce a printout. The drive shoulder 44 preferably extends axially along a curved generally helical path such that the hammer drive pawls 40 are engaged in succession rather than all at once to reduce the required drive torque for the shaft 12 and to reduce the shock on the mechanism. The helical shoulder 44 extends through an angle of approximately 90° and each hammer drive pawl 40 is driven by the drive-ratchet shaft 12 during approximately 60° of rotation of the shaft 12 such that the entire printing operation is performed during approximately 150° of rotation of the shaft 12.

The drive shoulder 44 and drive pawl shoulders 43 are contoured such that each pawl shoulder 43 becomes disengaged from the drive shoulder 44 just prior to the engagement of the hammer 22 with the paper 28 and the printing is performed by the inertia of the moving hammer. Also, the rebound of each hammer occurs sufficiently quickly after the disengagement of the pawl shoulder 43 from the drive shoulder 44 that the pawl 40 re-engages and is pivoted by the cam shaft 14 out of engagement with the drive-ratchet shaft 12 before the drive shoulder 44 can complete a revolution to re-engage the pawl shoulder 43. During such return movement of the hammer 22 the drive pawl 40 initially rides over the outer cylindrical surface 60 of the drive-ratchet shaft 12 which thereby pivots the pawl for re-engagement with the cylindrical cam edge 52 of the cam shaft 14 whereupon the cam edge 52 pivots the pawl 40 out of engagement with the drive-ratchet shaft 12. Also, the hammer actuation is such that all of the hammer drive pawls 40 are out of engagement with the cam shaft 14 at the same time to permit the cam shaft 14 to be rotated back to its normal latching position by the return spring 50 before the pawls 40 return to re-engage the cam shaft 14.

A pivotal actuator 70 mounted on the support shaft 24 has a curved tail end engageable with a pin 72 on the cam shaft 14 for rotating the cam shaft for releasing the drive pawls. An actuator drive pawl 76 identical to the hammer drive pawls 40 is pivotally mounted on the pivotal actuator 70 for engagement with the drive-

ratchet shaft 12 (in the manner of the hammer drive pawls 40) for pivoting the actuator 70 sufficiently to release the drive pawls. A control cam 80 mounted coaxially with the cam shaft 14 provides for selectively holding the actuator drive pawl 76 out of engagement with the drive-ratchet shaft 12 in the manner of the cam shaft 14, and a tension spring 82 biases the control cam 80 to its normal angular position where its cylindrical surface 84 engages the actuator drive pawl 76 to hold it out of engagement with the drive-ratchet shaft 12.

The control cam 80 is adapted to be rotated against the bias of the spring 82 to release the actuator drive pawl 76 by an electromagnet 85 having an armature 86 with a hooked end engageable with a pin 88 on the control cam 80. The armature 86 is biased to its withdrawn position in engagement with a guide or stop 90 by a tension spring 92. The electromagnet 85, when energized, withdraws the armature 86 to pivot the pin 88 and control cam 80 for releasing the actuator drive pawl 76 and then releases the pin 88 to permit the control cam 80 to return to its normal position. Upon de-energization of the electromagnet 85, the armature 86 rides over the pin 88 to position the armature for re-engaging the pin 88 when the electromagnet is re-energized. Thus, by either momentarily energizing the electromagnet 85 or holding it energized, the control cam 80 will be rotated and released to permit the actuator drive pawl 76 to momentarily rotate and release the cam shaft 14. Such ensures that the hammer drive pawls 40 are permitted to engage the drive ratchet shaft 12 for actuating the print hammers 22 only once for each operation of the electromagnet 85. Also, the actuator drive pawl 76 is operated by the drive-ratchet shaft 12 to timely release the hammer drive pawls 40 for initial engagement with the outer cylindrical surface 60 of the drive-ratchet shaft 12 thereby ensuring that the hammer drive pawls 40 are readied for proper engagement by the drive shoulder 44 for proper actuation of the print hammers 22.

As will be apparent to persons skilled in the art, various modifications, adaptations and variations of the foregoing specific disclosure can be made without departing from the teachings of the present invention.

I claim:

1. A print hammer mechanism comprising an elongated rotatable drive-ratchet shaft adapted to be continuously rotated during operation and having integral axially extending drive shoulder means, a plurality of axially spaced hammers extending transversely of the drive-ratchet shaft and pivotally mounted about an axis generally parallel to the drive-ratchet shaft axis to be pivotally actuated for producing a printout, a hammer drive pawl having an operating shoulder pivotally mounted on each hammer about an axis spaced from and generally parallel to the pivotal axis of the hammer, each drive pawl being mounted to extend from its pivotal axis transversely of the drive-ratchet shaft to be pivoted to bring its operating shoulder into engagement with the drive shoulder means of the drive-ratchet shaft for pulling the pawl lengthwise along an axis through its pivot axis for causing the print hammer to be pivoted about its axis for producing a printout, and print control means for selectively pivoting the drive pawls for selective engagement of the pawl operating shoulders

with the drive shoulder means of the rotating drive-ratchet shaft for selectively actuating the print hammers for producing a printout.

2. A print hammer mechanism according to claim 1 wherein the print control means comprises spring means biasing the drive pawls into engagement with the drive-ratchet shaft and releasable latch means for releasably holding the drive pawls against the bias of the spring means out of engagement with the drive-ratchet shaft.

3. A print hammer mechanism according to claim 1 wherein the print control means comprises a control shaft rotatable about an axis generally parallel to the axis of the drive-ratchet shaft and operable in one angular position thereof to hold the drive pawls out of engagement with the drive-ratchet shaft and rotatable in at least one angular direction from said one angular position thereof to release the drive pawls for engagement with the drive-ratchet shaft for actuation of the hammers, a pivotal control shaft actuator pivotal in one angular direction about an axis generally parallel to the drive-ratchet shaft axis for rotating the control shaft in its said one angular direction for releasing the hammer drive pawls, an actuator drive pawl having an operating shoulder pivotally mounted on the actuator about an axis spaced from and generally parallel to the axis of the pivotal actuator, the pivotal actuator drive pawl being mounted to extend from its pivotal axis transversely of the drive-ratchet shaft to be pivoted to bring its operating shoulder into engagement with the drive shoulder means of the drive-ratchet shaft for pulling the actuator drive pawl lengthwise along an axis through its pivot axis for pivoting the actuator in its said one angular direction for rotating the control shaft, a pivotal control cam operable in one angular position thereof for holding the actuator drive pawl out of engagement with the drive-ratchet shaft and rotatable in at least one angular direction for releasing the actuator drive pawl for engagement with the drive-ratchet shaft, and an electromagnetic operator adapted upon energization for rotating the control cam in its said one angular direction for releasing the actuator drive pawl.

4. A print hammer mechanism according to claim 1 wherein the drive shoulder means of the elongated drive-ratchet shaft comprises a shoulder extending axially along a generally helical path and engageable with the operating shoulders of the hammer drive pawls in succession for actuating the print hammers in succession.

5. A print hammer mechanism according to claim 1 wherein the control means comprises a rotatable cam shaft extending generally parallel to the drive-ratchet shaft and having first and second angularly spaced operative angular positions, the cam shaft having controlling means operable in said first angular position of the cam shaft for camming the drive pawls out of engagement with the drive-ratchet shaft and operable in said second angular position of the cam shaft for releasing the drive pawls for engagement with the drive-ratchet shaft, and cam operating means for selectively rotating the cam shaft to its said second angular position for releasing the drive pawls.

6. A print hammer mechanism according to claim 1 wherein the print control means comprises first releasable latch means for holding the hammer drive pawls out

of engagement with the drive-ratchet shaft, a latch actuator pivotally mounted about an axis generally parallel to the drive-ratchet shaft axis and connected to be pivotally actuated for releasing the first releasable latch means, an actuator drive pawl having an operating shoulder pivotally mounted on the latch actuator about an axis spaced from and generally parallel to the pivotal axis of the latch actuator for being pivoted to bring its operating shoulder into engagement with the drive-ratchet shaft for actuation thereby for actuating the latch actuator, and second releasable latch means for holding the actuator drive pawl out of engagement with the drive-ratchet shaft.

7. A print hammer mechanism according to claim 6 wherein the cam operating means comprises a cam actuator adapted to be actuated for rotating the cam shaft to its said second angular position, an actuator drive pawl on the cam actuator selectively engageable with the drive-ratchet shaft for actuation thereby for actuat-

ing the cam actuator, and actuator drive pawl control means for selectively engaging the actuator drive pawl with the drive-ratchet shaft.

8. A print hammer mechanism according to claim 7 wherein the actuator drive pawl control means comprises an electromagnetic operator operable upon energization thereof to engage the actuator drive pawl with the drive-ratchet shaft.

9. A print hammer mechanism according to claim 8 wherein the electromagnetic operator comprises releasable latch means for releasably holding the actuator drive pawl out of engagement with the drive-ratchet shaft.

10. A print hammer mechanism according to claim 6 wherein the print control means further comprises an electromagnetic operator connected for releasing the second latch means upon energization thereof.
